UNITED STATES PATENT OFFICE.

AXEL G. GULBRANSEN AND CHRISTIAN GULBRANSEN, OF CHICAGO, ILLINOIS, ASSIGNEES TO GULBRANSEN-DICKINSON COMPANY, OF CHICAGO, ILLINOIS, A CORPORATION OF ILLINOIS.

PLAYER-PIANO MECHANISM.

1,274,535.

Specification of Letters Patent. Patented Aug. 6, 1918.

Application filed October 15, 1914. Serial No. 866,752.

To all whom it may concern:

Be it known that we, AXEL G. GULBRANSEN and CHRISTIAN GULBRANSEN, both citizens of the United States, residing at Chicago, in the county of Cook and State of Illinois, have invented certain new and useful Improvements in Player-Piano Mechanism, of which the following is a full, clear, concise, and exact description, reference being had to the accompanying drawings, forming a part of this specification.

Our invention relates to automatic playing pianos and is particularly concerned with those which are operated, or at least controlled, by pneumatic means.

In devices of this kind, it is the general practice to provide a so-called operating pneumatic for each striking rod in the piano and to control the operation of said striking pneumatic by means of valves which, in turn, are moved by the admission of air to respective diaphragm chambers, this admission of air to these diaphragm chambers being controlled by a so-called "note-sheet" traveling over a so-called "tracker-board", the trackerboard having an opening for each note adapted to be covered and uncovered according to the formation of the note-sheet.

As the note-sheet travels from one side to the other of the tracker-board, it is, of course, necessary that it should "track" properly—that is, the note-sheet and the variously disposed openings therein must register properly at all times with the regularly arranged openings in the tracker-board. It is the object of our invention to provide automatic means for constantly maintaining this proper relation.

We are aware that so-called "automatic tracking devices" are old in the art, but our invention provides new and useful features which remedy defects in the automatic tracking devices of the prior art and which work toward the end of simple, reliable and efficient operation.

Most of the automatic tracking devices of the prior art are operated by pneumatic means controlled from the edge of the note-sheet, but this is subject to certain inherent defects, due to the fact that shrinking and warping of the note-sheet is most pronounced at the edge and due to the fact that the edge is not always cut absolutely

true, so that an automatic tracking device frequently does more harm than good. Our invention is of the type in which the automatic tracking device is operated by means of openings in the note-sheet, these openings being specially and accurately cut. While it is possible to utilize our invention by providing a special series of openings in the note-sheet for the exclusive function of operating the automatic tracking device, it is a special feature of our invention that the arrangement is such that the automatic tracking device may be controlled by the note openings themselves, preferably the center ones, and thus no special note-sheet is required. In this connection, our device has certain special features of construction and arrangement to the end of simplicity and efficiency and it will be seen that this desirable result is obtained, in the use of our invention, without the employment of a large number of parts or of a complicated arrangement.

Referring to the accompanying drawings, Figure 1 illustrates an elevational view of an automatic playing piano, embodying the features of our invention;

Fig. 2 is a view, on a larger scale, of the roller box and the mechanism for shifting the trackerboard;

Fig. 3 is a top view of the parts shown in Fig. 2; and

Fig. 4 is an enlarged view of the trackerboard and the music sheet.

Referring first to Fig. 1, it will be seen that we provide, within the usual piano casting 5, the usual pneumatic action 6, which is located directly in front of all the striker bars (not shown) and which comprises a plurality of operating pneumatics, one for each striker bar. The details of this action do not form part of the present invention and we have not, therefore, shown this mechanism in detail.

The instrument is operated by the creation of vacuum or partial vacuum, and the mechanism for performing this function is found in the pumbers 7, 7, which are operated by the pedals 8, 8. These parts maintain a constant low-pressure in the vacuum chamber 9, from which a tube 9' leads to the wind-chest of the pneumatic action 6, as indicated. The roller box 10 is mounted

upon a shelf 11 and the tracker-board 17 (referred to more fully later) is mounted approximately in the middle of this roller box, as shown in further detail in Fig. 2. The 5 tracker-board is provided with a plurality of openings 16, one for each note to be played, and these openings are connected by means of respective rubber tubes, 17', 17', with the corresponding controlling valves of 10 the corresponding operating pneumatics.

The roller box 10 supports near the top thereof a music roll 12, upon which the music sheet 14 is wound. This roll is supported on the right by means of a spindle 12' which carries a sprocket, and a chain 12^a connects this sprocket with another sprocket splined upon the motor shaft 12^b of the motor 12^c, said shaft also having splined thereon a pinion 12^d, which, when 20 in one position, meshes with a gear 12^e carried upon the shaft 13', and thus the music sheet is wound upon the roll 13.

A swinging arm 13^a is pivoted at 13^b which arm, when swung, to its alternate position reverses the direction of rotation of the rolls. This arm 13^a engages a clutch member between the pinion 12^d and the sprocket on the motor shaft, and when said arm is rotated about its pivot the pinion 12^d 30 will be disengaged from the gear 12^e and the clutch will thereupon engage the sprocket and the music sheet will thus be rewound upon the roll 12 after the music has been played.

35 As is shown particularly in Fig. 2, the music sheet 14 is provided with a plurality of openings 15, which are adapted to register with a plurality of openings 16 in the trackerboard 17. The trackerboard is mounted at one end on pins 18, 18, and at the other end on pins 19, 19, these pins being mounted on the sides of the roller box, as shown, to permit of the lateral movement of the tracker relative to the box. One end 40 of the trackerboard has secured thereto a rod 20, which has pivoted thereto a link 21, which in turn is pivoted at 22 to a bracket 23 secured to the movable board of the bellows 24. This bellows board is connected by 45 means of a link 25 with the movable board of a similar bellows 26, both boards being hinged to a stationary part 27. A channel 28 communicates with the bellows 26 and leads to a compartment 29 which is normally 50 connected to atmosphere through the opening 30. This opening is adapted to be closed by a valve 31, secured to a stem 32, the lower end of which is engaged by a diaphragm 33 covering a diaphragm chamber 34. A 55 bleeder opening 35 connects with the diaphragm chamber 34 with a suction chamber 36, which, in turn, is connected to the vacuum chamber of the pneumatic action 6 by means of the tube 37. The bellows 24 60 communicates, by means of the channel 38

(Fig. 3) with the compartment 39, which has an outlet at 40 to atmosphere. This outlet is adapted to be closed by the valve 41, the stem of which engages with a diaphragm 42 covering a diaphragm chamber 43. A 70 bleeder opening 44 forms a restricted passage from this chamber to the suction chamber 36. It will thus be seen that, since the tube 37 communicates with the vacuum chamber of the pneumatic action, there will 75 be a partial vacuum in the chambers 34, 36 and 43.

Referring again to the trackerboard, and particularly to Fig. 4, it will be observed that we have provided two sets of narrow 80 slots 45 and 46, on either side of the center line passing between the two central openings in the trackerboard. The slots 45 communicate with a chamber 47, the rear of 85 which is closed by a plate 48. This chamber communicates, by means of a tube 49, with the diaphragm chamber 34. The slots 46 communicate with a chamber 50, which is also closed by the plate 48, and this chamber 90 communicates with the diaphragm chamber 43 by means of the tube 51. It will thus be understood that, when the slots 45 and 46 are not exposed to atmospheric pressure, the 95 air pressure will be reduced in the chambers 47 and 50 and tubes 49 and 51. It will be observed from Fig. 4 that the openings 16 are slightly wider than the openings 15 in the music sheet and that the narrow slots 45, on the right of the center line, are disposed 100 in position just inside the right hand margin of corresponding player openings 16, while the slots 46, on the left of the center line, are disposed just inside the left hand margin of corresponding player openings 16.

In order to secure the proper tonal effects, 105 it is desirable that the openings in the music sheet pass directly over the openings in the tracker bar in order to operate the playing mechanism, but it has been found in practice, however, that the music sheet will shift from 110 one side to the other, and thereby destroy to some extent the proper tonal effect. By our invention, the music sheet is moved to its normal position when for any reason it has been shifted out of its proper course. 115 Assuming, as the music sheet is being drawn from the music roll 12 by the unwinding roll 13, that the paper 14 has shifted so that one of the openings 15 takes a position as shown in dotted lines at 52, it will be clear that 120 one of the slots 46 will thereupon be exposed so that the air will rush through the same and through the tube 51 into the diaphragm chamber 43. This will cause the diaphragm 43 to be raised and, consequently, the valve 125 41 will close the opening 40, whereupon the bellows 34 will be in direct communication with the suction means and this bellows will then collapse, or partly collapse, so as to cause the trackerboard 17 to shift toward 130

the left until the slot 46 has been closed. The openings 15 are thus brought back into proper relation with the opening 16 in the trackerboard. In case the music sheet

5 should shift in the opposite direction, that is toward the right, the slots 45 will then be exposed to atmosphere and the bellows 26 will be collapsed, owing to the diaphragm 33 being raised, when the bellows will be in

10 communication with the suction means so as to exhaust the air from said bellows and cause a shifting of the trackerboard 17 toward the right until the slot or slots 45 are covered by the music sheet as it travels

15 across the trackerboard. The movement of the trackerboard to the right may be limited, as by means of a screw 53.

After the openings have been closed by the paper, the valve 31 or 41 (whichever the 20 case may be) will be restored owing to the fact that the air pressure will be reduced in the compartment 34 or 43 and also in the corresponding tube, thus permitting air at atmospheric pressure to enter the bellows.

25 By this arrangement it will be clear that the openings in the music sheet 14 are always kept in proper registration with the openings in the trackerboard.

After the music has been played and the 30 music sheet has been rewound upon the roller 12 by the mechanism previously described, said roller is removed by pushing the spring pressed spindle 14^a toward the left.

35 We claim as new and desire to secure by Letters Patent:

1. In a player piano, the combination of 40 suction means, a movable trackerboard, a music roll and an unwinding roll, a music sheet, means for moving said sheet from one roll to the other, a pair of bellows adapted to be connected with said suction means, said trackerboard having two sets of auxiliary openings arranged on opposite sides of the 45 center thereof, each set being exclusive to its own side and being connected to a common chamber in the trackerboard and each chamber being connected to said suction means, said openings being entirely covered when 50 said music sheet is tracking properly, valves operable when said openings are exposed to place either of said bellows in communication with said suction means, and means connected with said bellows for securing a relative adjustment between said music sheet 55 and said trackerboard when the auxiliary openings are exposed to atmosphere.

2. In a player piano, the combination of 60 suction means, a trackerboard, a music roll and an unwinding roll, said rolls and said trackerboard having movement relative to each other, controlling bellows for securing said movement normally open to the atmosphere, a diaphragm chamber for each bellows, a valve for each diaphragm chamber,

said trackerboard having two sets of auxiliary openings normally entirely covered by said music sheet and arranged on opposite sides of the center thereof, each set of openings being exclusive to its own side and 70 being connected to a common chamber in the tracker which in turn is connected to one diaphragm chamber, and means connecting the diaphragm chambers with the suction means, said controlling bellows serving to secure said movement in either direction in accordance with the exposure of either set of said auxiliary openings to atmospheric pressure. 75

3. In a player piano, the combination of 80 suction means, a movable trackerboard, a music roll and an unwinding roll, a pair of shifting bellows normally open to the atmosphere, a diaphragm chamber for each bellows, a valve for each diaphragm chamber, 85 said trackerboard having two sets of auxiliary openings normally entirely covered by said music sheet and arranged on opposite sides of the center thereof, each set of openings being exclusive to its own side and 90 being connected to one diaphragm chamber, and means connecting the diaphragm chambers with the suction means, said bellows being directly connected to said trackerboard to shift the trackerboard in either 95 one of both directions in accordance with the exposure of either set of auxiliary openings to atmospheric pressure.

4. In a player piano, the combination of 100 suction mechanism, a movable trackerboard, a music roll and an unwinding roll, a music sheet, means for causing said sheet to travel over said trackerboard and from one roll to the other, shifting bellows connected to said trackerboard, said bellows being connected and normally open to atmosphere, a diaphragm chamber associated with each bellows, a valve for each bellows controlling the air inlet thereto, said trackerboard having two sets of auxiliary openings, arranged 105 on opposite sides of the center of the trackerboard, each set being exclusive to its own side and being connected to one diaphragm chamber and being arranged to be exposed through the player openings of the note sheet only when the note sheet shifts, said diaphragm chambers having a common connection to the suction mechanism, and a device for limiting the movement of said trackerboard in one direction. 110

5. In a player piano, a music roll, a movable trackerboard, a music sheet, means for drawing said music sheet across said trackerboard, said trackerboard having narrow auxiliary openings, positioned in vertical 115 alignment with and just inside the margin of corresponding tracker openings and normally entirely covered by the music sheet, suction means, and devices connecting said suction means and said auxiliary openings, 120 125 130

said devices serving to shift said trackerboard when the music sheet exposes said auxiliary openings to the atmosphere.

6. In a player piano, a longitudinally movable trackerboard, a music sheet, means for drawing said music sheet over said trackerboard, said trackerboard being provided with two sets of narrow auxiliary openings normally entirely covered by the music sheet, one set being on each side of the center of the tracker and positioned in vertical alinement with and just inside the margin of corresponding tracker openings, suction means connected with said auxiliary openings, and mechanism interposed between said suction means and trackerboard for shifting said trackerboard when the auxiliary openings are exposed to the atmosphere.

20 7. In a player piano, the combination of suction means, a trackerboard, a music roll and an unwinding roll, a perforated music sheet passing between said rolls and over said trackerboard, said rolls and said trackerboard having relative shifting movement therebetween, a pair of bellows adapted to effect said shifting movement, valves for

connecting said bellows to said suction means, said tracker board having two sets of auxiliary openings normally covered by 30 said music sheet when the same is correctly alined on said tracker bar, each of said sets of openings arranged along different sections of said trackerboard and connected to separate chambers in said trackerboard, the 35 openings in one of said sets being controlled by the left hand edges of the music sheet perforations passing over the corresponding trackerboard section, the openings in the other of said sets being controlled by the 40 right-hand edges of the music sheet perforations passing over that corresponding trackerboard section, and pneumatic connections between said chambers and said valves for operating the latter when either of said sets 45 of openings is exposed to atmospheric pressure.

In witness whereof, we hereunto subscribe our names this 6th day of October, 1914.

AXEL G. GULBRANSEN.
CHRISTIAN GULBRANSEN.

Witnesses for both:
